(57) **CLAIM**

The ornamental design for an open two-way mailer, as shown and described.

DESCRIPTION

FIG. 1 illustrates a front perspective view of the open two-way mailer, in the opened condition.

FIG. 2 illustrates a rear perspective view of the open two-way mailer, in the opened condition.

FIG. 3 illustrates an enlarged top view of the open two-way mailer, in the opened condition.

FIG. 4 illustrates an enlarged bottom view of the open two-way mailer, in the opened condition.

FIG. 5 illustrates a side view of the open two-way mailer, in the opened condition; and,

FIG. 6 illustrates a side view of the open two-way mailer, in the opened condition.

The evenly spaced broken lines in FIGS. 1 and 2 are intended to represent perforations. The long and short broken lines in FIG. 2 are for illustrative purposes only and form no part of the claimed design.
